UNITED STATES PATENT OFFICE.

HENRY W. ROUNTREE, OF RICHMOND, VIRGINIA, ASSIGNOR TO H. W. ROUNTREE & BROTHER TRUNK & BAG CO., INCORPORATED, OF RICHMOND, VIRGINIA.

CLOTHES FOLLOWER OR PRESSER.

Application filed March 22, 1922. Serial No. 545,803.

To all whom it may concern:

Be it known that I, HENRY W. ROUNTREE, a citizen of the United States, residing at Richmond, in the county of Henrico and 5 State of Virginia, have invented a new and Improved Clothes Follower or Presser, of which the following is a specification.

This invention has special reference to improvements in (what is termed in the art) 10 follower or presser devices, that operate within the clothes compartment of wardrobe trunks which have garment supporting trolleys or hanger members, and which are especially designed to hold the garments from 15 being crumpled or mussed while the trunk is in transportation or is set up to serve as a wardrobe.

My present invention primarily has for 20 its purpose to provide a garment pressing or holding device of a comparatively simple and economical construction, that is permanently attached within the garment compartment of the trunk, and in such manner that it is always suspended within the 25 clothes compartment that the adjustment thereof, to either the clothes pressing or follower position, or the swung down and released position, for giving free access to the inside of the trunk compartment, is so simple that any one can almost instantly manipulate the device to either of its said 30 adjustments without the slightest danger of injury to the hanging garments, when the same is adjusted as a follower for engaging 35 the garment so hung, or when the garments are being hung upon or removed from the trolleys or supporting rods, such as are used in wardrobe trunks.

With other objects in view that will here- 40 inafter appear, my improved construction of clothes follower or presser device embodies the peculiar features of construction and novel combination of parts, fully stated in the following detailed description, specifically mentioned in the appended claims 45 and illustrated in the accompanying drawings, in which:

Figure 1 is a perspective view of my im- 50 proved construction of clothes follower or presser device, the same being shown as operatively applied to a wardrobe trunk, and located at its outermost clothes pressing position.

Figure 2 is a vertical section of a portion 55 of the clothes compartment of the trunk, the

presser or follower device being shown at the clothes pressing position in full lines and at the dropped or released position (for giving free access to the clothes compartment) in dotted lines.

Figure 3 is a face view of the clothes compartment of a wardrobe trunk with a modified adaptation of my invention shown thereon.

Figure 4 is a perspective view of my pres- 65 ent construction of follower device, the same being separated from the trunk, one of the segmental or fixedly held locking plates being also shown.

Figure 5 is a detail cross section of one 70 of the hinge arm pivots hereinafter specifically referred to.

In the illustrations of the operative ap- 75 plication of the simplest and preferred form of my invention, as illustrated in Figures 1 and 2 of the drawings, 1 designates the garment compartment of a conventional type of wardrobe trunk in the upper ends of the opposite sides of which are located the usual trolley rods on which the clothes hangers 80 2-2 are removably supported in the usual manner.

My present construction of clothes presser or follower device includes a cross bar 3 the entire front and back faces of which are 85 covered with a nickelized band 4, to present smooth surfaces for engaging the clothes. The band 4 is secured to the wooden bar by flat head rivets 5 which pass through the band and through the nickelized bearing brackets 6 that are secured on the opposite ends of the front face of the cross bar and which constitute the keepers for the oppositely projected locking rods 7-7.

The adjacent inner ends of the locking 95 rods 7-7 slidably engage a metal housing 8 that is riveted to the front face of the cross bar 3, centrally thereof, as is best shown in Figure 4, from which it will be seen the said inner ends of the rods 7-7 terminate 100 in right angled finger grips 70-70 that project through elongated slots 80 in the housing 8, the said fingers providing for conveniently pulling the bars 7-7 out of their locking adjustments and for compressing 105 the rods' distending spring 9 that is located between the adjacent ends of the rods 7-7 and within the housing 8, as shown.

In the simplest form of my invention, shown in Figures 1 and 2, an arm 10 is riv-

eted to the front face of each end of the bar 3 and the said arms (hereinafter termed hinge arms) are each pivotally connected with a hinge pin 11 located at their respective sides of the clothes compartment, the said hinge connection being such that when the cross bar 3 is released from the locking racks 13, presently again referred to, the said hinge arms 10 with the cross or presser bar 3, can be readily swung out, in the direction of the arrow, to drop down to the pendent or released position, as is clearly indicated in Figure 2 and in such manner that access may be conveniently had to the clothes compartment of the trunk for hanging the dresses or other garments within such compartment or for lifting the hangers with the clothes hung thereon from the hanger trolleys or supporting members, without the least danger of injuring the garments, when passing them into, or lifting them out of, the said clothes compartment.

The hinge connection for the swingable presser device is located at the outer or front edge of the opposite sides of the clothes compartment and by reason thereof the said device or cross bar, which is permanently contained within the trunk, is so positioned that it may be conveniently grasped and swung up to the clothes pressing position, shown in full lines in Figure 1 and held so the operator can readily push the cross bar 3 back to closely press the garments together, as indicated in the said Figure 1.

For locking the cross bar 3 to its inwardly swung clothes pressing adjustments, a segment shaped plate 12 is secured upon each of the opposite sides of the clothes compartment. Each plate 12 has a series of rack teeth or locking notches 13 that are disposed in an arc, with the cooperating hinge pin 11 as the center, it being understood that the projected rounded ends of the locking rods 7—7 travel along their respective rack plates 12 and automatically interlock therewith as the cross bar 3 is forced inwardly against the hung garments and by proper finger manipulation of the angled ends 70 the said rods 7 can be instantly pulled out of engagement with their respective arc shaped racks, when it is desired to swing the cross bar 3 out to the released position, and permit the said bar to drop down to its inoperative or out of the way adjustment, as shown in dotted lines on Figure 2.

In Figure 3, I have illustrated my improved presser and follower device used in connection with a supplemental follower board that has the shape of and can be used as an ironing board when it is disconnected from the trolley supports, and which is normally supported upon the said trolley sup-

ports or hangers, as is clearly indicated in the said Figure 3.

The hinge arm pivot pin 11 may be shouldered to abut its carrying bracket 14 mounted upon the respective side of the trunk clothes compartment wall and may have its reduced shoulder shank threaded to receive a nut 15 for holding the pivot pin 11 fixedly upon its said carrying bracket 14, as is clearly shown in Figure 5.

From the foregoing description, taken in connection with the accompanying drawings, the complete arrangement of my present form of clothes pressing follower device, the advantages of the construction and manner in which the said device is mounted within the clothes compartment of a wardrobe trunk will be readily apparent to manufacturers and users of trunks of the character stated.

What I claim is:—

1. A follower device of the character stated comprising a pair of rigid side arms, a cross bar connected at its opposite ends with the said pair of side arms, means for hingedly connecting the free ends of the side arms to the opposite ends of the clothes compartment of a wardrobe trunk at a point of fixed location whereby to swing the cross bar, when the arms are projected upwardly from their hinged connection inwardly against the hung garments in the clothes compartment of the trunk, locking elements cooperative with the bar and the opposite ends of the clothes compartment for holding the bar to its clothes pressing adjustments, the said elements including finger engaged members for releasing the locking elements and for pulling the released cross bar outwardly to permit it to drop to a pendent position below the hinged connections therefor.

2. In a wardrobe trunk wherein is provided a clothes hanging compartment, a presser or follower device that comprises opposite rigid end arms, pivot brackets secured on the opposite ends of the trunk, fixed pivot studs secured to said brackets, on which studs said arms are at one end pivoted, a cross bar rigidly connected to the other ends of said arms, bearing brackets secured to said arms and cross bar, a housing secured to said cross bar between the ends of the same, a pair of latch rods enclosed in said bearing brackets and said housing, a push spring in said housing between the ends of said latch rods, said latch rods having finger grips projecting through elongated slots in said housing, arcuate rack plates secured to the opposite end walls of said clothes compartment to cooperate with the ends of said latch rods for the purposes specified.

HENRY W. ROUNTREE
